UNITED STATES PATENT OFFICE

154,979

DESIGN FOR A COOKING RANGE

William Bauer, Mansfield, Ohio, assignor to The Tappan Stove Company, Mansfield, Ohio, a corporation of Ohio

Application July 16, 1947, Serial No. 140,329

Term of patent 14 years

(Cl. D81—4)

To all whom it may concern:

Be it known that I, William Bauer, a citizen of the United States and a resident of Mansfield, in the county of Richland and State of Ohio, have invented a new, original, and ornamental Design for a Cooking Range, of which the following is a specification, reference being had to the accompanying drawing, forming a part thereof, which shows a perspective view of a cooking range showing my new design.

The lefthand side of the range, which does not show in the drawing, is the same as the righthand side thereof.

I claim:

The ornamental design for a cooking range, as shown and described.

WILLIAM BAUER,
